UNITED STATES PATENT OFFICE.

ADAM BEACH, OF COLUMBUS, OHIO, ASSIGNOR TO ALFRED R. CORY AND EDWARD S. DEVEREAUX, OF NEW YORK, N. Y., AND THOMAS A. SIMONS, OF COLUMBUS, OHIO.

STORE-SERVICE APPARATUS.

SPECIFICATION forming part of Letters Patent No. 416,546, dated December 3, 1889.

Application filed July 27, 1888. Renewed October 17, 1889. Serial No. 327,263. (No model.)

To all whom it may concern:

Be it known that I, ADAM BEACH, a citizen of the United States of America, residing at Columbus, in the county of Franklin and State of Ohio, have invented certain new and useful Improvements in Store-Service Apparatus, of which the following is a specification, reference being had therein to the accompanying drawings.

10 My invention relates to store-service apparatus in which a projecting device is used to give a carrier an initial impetus sufficient to propel it over a way upon which it travels.

The object of my invention is to produce a 15 simple and inexpensive device in which the carrier-projecting spring and also the advancing spring of the sliding catch are passed around pulleys and secured to the rear end of the device to increase the resilience and 20 lasting qualities of said springs; second, to provide the device with means to facilitate the retraction of the sliding catch. I attain these objects by the construction illustrated in the accompanying drawings, in which—

25 Figure 1 is a perspective view of the projecting device, a portion of the wire way and the sliding catch thereon constructed in accordance with my invention. Fig. 2 is a longitudinal vertical section of the same. Fig.

30 3 is a similar section on a smaller scale, showing also the carrier upon the wire way.

The frame of the device consists of two slightly-divergent bars A, united at one end to a transverse bar A², preferably formed integral therewith. This transverse bar has a vertical boss A³, internally screw-tapped to receive one end of a rod pendent from the ceiling or other part of a store. One end of the wire way B passes centrally through the 35 transverse bar A², and is clinched or otherwise secured thereto. The outer end of each bar A has a horizontal slot a, within which is placed a sheave a².

The spring C, used to propel the carrier, consists of a strong rubber cord having its ends retained in clamps c. Each is provided with a rod c², that is adjustably retained in a socket a³, projecting from the side of the bar A at the rear end thereof, a screw a⁴ passing

50 radially through said socket and entering one of the perforations in the rod c² of the rubber spring-clamps. The spring C thus extends along the side of the bars A, and is normally under tension between the sheaves a², around which it passes. The wire way B passes 55 under the spring C and sustains the carrier D, the latter having horns D² at each end to come into engagement with the spring C and wheels d to travel upon said way, and at each end a bevel-pointed hook having its nib d² 60 projecting upward.

To retain the carrier at either end of the wire way in proper position for immediate use, there is also suspended from said way a small carriage E, having upon its top two lugs e 65 and e², perforated for the passage of the wire way, and pendent from its bottom a slotted arm e³, and within said slot is pivoted at f a bell-crank-shaped catch-lever F, having its hooked nib f² projecting downward in the 70 rear of its beveled end. The pendent arm of the catch F has pivoted to its lower end a short horizontal rod f³, upon which is placed a coil-spring f⁴, one end of which bears against the rear of the arm e³ and the other against 75 a collar adjacent to the head f⁵ upon the end of the rod f³, said rod being guided by a sleeve f⁶, projecting from the rear of the arm e³.

To keep the catch-carrying carriage E in its normal forward position, a rubber spring-cord G passes through a hole made transversely through the lug e² of said carriage. Said spring G passes also around small sheaves g, mounted upon the front portion of the bars A, and thence to eyes g² upon the 85 rear portion, to which eyes the ends of said spring are fastened.

To pull back the catch-carrying carriage E (and with it the carrier D) without much exertion on the part of the salesman, the end 90 bar A² of the frame has a pendent arm A⁴, that is vertically slotted, and carries in said slot a sheave h. The small carriage E has also projecting from the rear thereof a slotted arm E², in the slot of which is pivoted a sheave 95 e⁴. One end of a cord H is secured to an eye a⁵ on the inner side of the arm A⁴, from which said cord passes around the sheave e⁴ and

back on top of the sheave h , from which it hangs down to within a convenient reach of the salesman.

To regulate the degree of tension brought to bear upon the spring C at the time the carrier is released, (as upon the degree of the tension will depend the distance which the carrier can be thrown and its velocity,) a square rod I is made to pass horizontally through the lower portion of the arm A^4 and in line with the head f^5 of the rod f^3 , attached to the lower arm of the bell-crank catch E . This rod I is retained adjustably in the arm A^4 by means of a screw i , passing through said arm and impinging against said rod, so that the concave front end of the rod I can be retained at a more or less distance from the position occupied normally by the head f^5 of the rod f^3 . The rear end of the rod I has a longitudinal vertical slot i^2 , through which the cord H passes, and when a knot h^2 upon said cord comes in contact with the bottom of the rod I it arrests the forward motion of the small catch-carriage E at the proper place for its catch F to engage with the hook of the carrier.

Having now fully described my invention, I claim—

1. In a store-service apparatus, the combination of a wire way, a frame having divergent bars and sheaves at the outer end of said bars, and sockets secured to the sides of said bars, with a spring retained normally under tension upon said sheaves, and clamps 35 for the ends of said spring retained adjustably within said sockets, substantially as and for the purpose described.
2. In a store-service apparatus, the combination of a wire way, a frame having divergent arms, sheaves within slots in the ends thereof, and a propelling-spring retained normally under tension between said sheaves and extending alongside of said sheaves, with 40 a sliding catch-carriage mounted upon the wire way, substantially as and for the purpose described.
3. In a store-service apparatus, the combination of a wire way, a frame having arms with slots in their outer ends, sheaves there-

in and a propelling-spring resting upon the periphery of said sheaves, with a sliding catch-carriage mounted upon the wireway, the sheaves g upon the frame, and a cord-spring having its middle portion connected with the catch-carriage and passing around said sheaves g to the rear end of the frame, substantially as and for the purpose described.

4. In a store-service apparatus, the combination of a wire way, the frame having arms in the same horizontal plane as said way, a projecting spring and a catch-carriage-advancing spring, with a catch-carriage mounted upon the wire way, a bell-crank-shaped catch-lever pivoted to said carriage, the rod f^3 , pivoted to said lever, and a coil-spring upon said rod, substantially as and for the purpose described.

5. In a store-service apparatus, the combination of a wire way, a frame having horizontal arms with two pairs of sheaves upon their outer ends, a projecting spring and a catch-carriage-advancing spring passing around said sheaves, a catch-carriage, a bell-crank-shaped catch-lever pivoted to said carriage, the rod f^3 , pivoted to said lever, and a spring to advance said rod, with a stop-rod I adjustably secured to the frame and having a slot therein for the passage of the retracting-cord H , substantially as and for the purpose described.

6. In a store-service apparatus, the combination of a wire way, a frame having horizontal arms with two pairs of sheaves upon their outer ends, a propelling-spring and catch-carriage-advancing spring passing around said sheaves, a catch-carriage, a sheave mounted upon the rear end of said carriage, and a cord doubled over said sheave and having one end secured to the frame and the other passing over a second sheave, substantially as and for the purpose described.

In testimony whereof I affix my signature in presence of two witnesses.

ADAM BEACH.
